UNITED STATES PATENT OFFICE.

EDMUND R. NEBELING, OF NEW YORK, N. Y.

SEPARABLE FASTENER.

Application filed November 10, 1921. Serial No. 514,235.

To all whom it may concern:

Be it known that I, EDMUND R. NEBELING, a citizen of the United States, and a resident of the city of New York, Woodhaven, borough of Queens, in the county of Queens and State of New York, have invented a new and Improved Separable Fastener, of which the following is a full, clear, and exact description.

10 The present invention relates to new and useful improvements in separable fasteners, and it pertains more particularly to clasps for jewelry, such, for example, as bracelets, necklaces, and the like.

15 It is one of the primary objects of the invention to provide a clasp for bracelets formed of pearls or similar beaded structures.

It is a further object of the invention to 20 provide a separable fastener in which the two parts thereof are positively locked together against accidental displacement.

It is a still further object of the invention to construct a clasp in such a manner 25 that the locking element moves in a direction at substantially right angles to the direction of strain to which the clasp is subjected in use.

With the above and other objects in view, 30 reference is had to the accompanying drawings, in which—

Figure 1 is a view in elevation of a portion of a bracelet showing the clasp and its method of attachment thereto;

35 Fig. 2 is a view in elevation of one of the members of the clasp;

Fig. 3 is a view in elevation of the other member of the clasp;

Fig. 4 is a longitudinal sectional view of 40 the clasp taken on the line 4—4 of Fig. 2;

Fig. 5 is a perspective view of the several parts of the clasp in disassembled relation.

Referring more particularly to the drawings, the clasp comprises a base 10 and said base 10 is provided with two side flanges 11, and an end flange 12. This base 10 is cut out as indicated by the reference character 13 to provide a substantially T-shaped opening therein, the purpose of which will be 45 hereinafter described. The base member 10 is also provided with two openings 14 and 15, preferably of circular contour, said openings being formed substantially centrally with respect to the side flanges 11. The reference character 15' designates a plate 50 adapted for sliding movement within the

base member 10. This plate is cut out as at 16, to provide a tongue 17, and at the rear of said tongue 17, the plate is cut out to provide an opening 18. The plate 15' is depressed as at 19, to provide upon its under face a projection 20. The reference character 21 designates a closing plate or guide plate, and said plate 21 is cut out to provide a T-shaped slot 22 of substantially the same 55 size as the T-shaped slot 13 of the base member 10. The reference character 23 designates a latch plate, and said latch plate is provided with a projecting lug or the like 24.

In assembling this member of the fastener, the plate 15' is positioned within the base member 10, after which the closing plate 21 is positioned upon the flanges 11 and 12 and suitably secured thereto by means of solder or any other suitable fastening element. After the parts have been so positioned, the plate 23 is positioned on the top of the plate 21 with its lug 24 positioned within the opening 18 of the plate 15'. This plate 23 is secured to the plate 15' by solder 60 or upsetting the lug 24.

The other member of the clasp comprises a plate 30 provided with an eye or the like 31.

Each of the members is provided on one 65 edge with a wire 32, so shaped as to provide eyelets or the like 33, to which the strands 34 of the pearls or beads may be secured as indicated in Fig. 1.

To secure both parts of the clasp together 70 as in Fig. 1, the eye 31 is inserted in the opening 13 of the base 10. After this has been done, the plate 23 is moved longitudinally of the plate 21, and owing to the engagement of the lug 24 in the eye 18 of the plate 15', the plate 15' will be reciprocated longitudinally of the base 10 and the tongue 17 will be moved through the eye 31, thus 75 securing the two members of the clasp in locked relation one to the other.

When the clasp is in its open position, the projection 20 of the plate 15' engages the opening 14, thus maintaining the several parts in the open position. When, however, the clasp is closed, as above described, the 80 projection 20 enters the opening 15 and prevents accidental opening of the clasp member.

As shown in Fig. 1, the plate 23 may be provided with an operating lug or projection 85 35, by means of which the said plate 23 may be more readily reciprocated.

From the foregoing it is apparent that the present invention provides a new and improved form of separable fastener especially adapted for forming the closing means for bracelets, necklaces, and the like, formed from a plurality of single strands of pearls or beads. Furthermore, the clasp is simple in construction and of relatively low cost of manufacture.

10 I claim:

1. In a separable fastener, a base member, a sliding plate mounted in the base member, a closing plate, and an operating member slidably mounted on the closing plate and rigidly secured to the sliding plate whereby upon movement of the operating member the sliding plate will be moved to locking and unlocking position.

2. In a separable fastener, a base plate having an opening therein, a sliding plate mounted in said base and having a tongue adapted to move across said opening, means for moving said sliding plate, and a member carrying an eye, said eye being adapted to be received in the opening in the base and receive the tongue of the sliding plate to retain the two members of the fastener in closed position.

3. In a separable fastener, a base provided with side flanges and an end flange, said base being provided with a slot, and a plurality of spaced depressions, a sliding plate mounted in said base, the flanges of said base providing guides for said sliding plate, means for sliding said plate relatively to the base, and means carried by said sliding plate and adapted for alternate engagement with said depressions to prevent accidental movement of the plate relative to the base.

4. A separable fastener comprising a base provided with a substantially T-shaped slot, a sliding plate mounted in the base, a tongue carried by said plate and adapted for movement relative to the T-shaped slot of the base, said plate being provided with a square opening, a closing plate adapted for positioning upon the flanges of the base, said closing plate being provided with a T-shaped slot, an operating plate slidably mounted upon the closing plate, and a lug carried by said operating plate, said lug projecting through the T-shaped slot in the closing plate and received within the square opening of the sliding plate whereby movement

of the operating plate will reciprocate the 55 sliding plate to move the latch thereof relatively to the T-shaped opening in the base.

5. A separable fastener comprising a base having a transverse and a longitudinal slot, said slots communicating one with the other, 60 a plate adapted to be received within the base, said plate being provided with an opening adapted for registration with the longitudinal slot of the base, a latch formed on said plate and adapted to move transversely 65 of the transverse slot of the base, and means for moving said second-mentioned plate relatively to the base to move the latch member transversely of the transverse slot of the base, as and for the purpose set forth. 70

6. In a separable fastener, a base having a transverse and a longitudinal slot, said slots being in communication one with the other, a member having an eye adapted for positioning within the transverse slot of the 75 base, and means carried by said base and movable transversely of the transverse slot and passing through the eye of the second-mentioned member to secure said members one to the other. 80

7. In a separable fastener, a base plate having an opening therein, a sliding plate mounted in said base and having a tongue adapted to move across said opening, means for moving said sliding plate, a member 85 carrying an eye, said eye being adapted to be received in the opening in the base and receive the tongue of the sliding plate to retain the two members of the fastener in closed position, and means for retaining the 90 sliding plate against accidental movement relative to the base.

8. In a separable fastener, a base plate having an opening therein, a sliding plate mounted in said base and having a tongue 95 adapted to move across said opening, means for moving said sliding plate, a member carrying an eye, said eye being adapted to be received in the opening in the base and receive the tongue of the sliding plate to 100 retain the two members of the fastener in closed position, and means for retaining the sliding plate against accidental movement relative to the base, said means comprising a projection on the sliding plate adapted for 105 engagement with one of a plurality of openings in the base.

EDMUND R. NEBELING.
